UNITED STATES PATENT OFFICE

JAMES WOODFORD AND WILLIAM H. BANCROFT, OF PORTLAND, WIS.,
ASSIGNORS TO SAID BANCROFT AND W. L. WARD.

IMPROVEMENT IN STEAM-GENERATORS.

Specification forming part of Letters Patent No. 59,146, dated October 23, 1866.

To all whom it may concern:

Be it known that we, JAMES WOODFORD and WILLIAM H. BANCROFT, of Portland, in the county of Dodge and State of Wisconsin, have invented a new and useful Improvement in Steam-Boilers; and we do hereby declare that the following is a full, clear, and exact description of the same, reference being had to the annexed drawings, making part of this specification, in which—

Figure 1 is a perspective view. Fig. 2 is a view of the end piece. Fig. 3 is a horizontal section, and Fig. 4 is a vertical cross-section.

The same letters are used in the several figures in indicating identical parts.

Our boiler is constructed with especial reference to the use of hydrocarbon oils as a fuel for generating steam; but the mode adopted of increasing the fire-surface is applicable, with slight modifications, to all kinds of fuel.

The following description will enable persons skilled in the art to construct the same.

A is a lamp for containing the oil used as fuel. B is the wick-tube, extending the entire length of the boiler, and B' wheels by which the height of the wick is regulated in the ordinary manner.

D is the boiler, which is cylindrical on its exterior surface. It is constructed with an internal fire-chamber, F, extending through the entire length of the boiler, through which the flame passes into the flues F¹, which lead into the internal flue, F², the smoke escaping through the smoke-stack G.

The boiler being set in the usual manner, the

heat will be applied to the lower surface as well as on both faces of the fire-chamber F, and on the surfaces of the flues F¹, and also around the internal flue, F², extending the entire length of the boiler, or nearly so.

The water will fill the spaces E and also the space E' and cover the top of the flue F².

By this means a very large area of fire-surface is exposed to the water.

The plates H fit into and close the ends of the fire-chamber F.

C is a jacket surrounding the wick-tube. The cold water entering at C² passes entirely around the tubes B, and is heated in its passage before being drawn out through the pipe C¹. By this means we are enabled to feed the boiler with hot water.

The hood I, setting over the jacket C, directs a current of air against the base of the flame.

What we claim as our invention, and desire to secure by Letters Patent, is—

1. A boiler, D, when constructed with an internal fire-chamber, F, flues F¹, and an internal flue, F², and arranged substantially as set forth.
2. In combination with a boiler, D, a jacket, C, surrounding the wick-tube B, for heating the water before it is applied to the boiler, substantially in the manner set forth.

JAMES WOODFORD.

WILLIAM H. BANCROFT.
